UNITED STATES PATENT OFFICE.

OLE S. LE GRAND, OF ROLLAG, MINNESOTA.

CHISEL AND PUNCH HOLDER.

1,196,252.

Specification of Letters Patent. Patented Aug. 29, 1916.

Application filed May 18, 1914. Serial No. 839,634.

To all whom it may concern:

Be it known that I, OLE S. LE GRAND, a citizen of the United States, residing at Rollag, in the county of Clay, State of Minnesota, have invented certain new and useful Improvements in Chisel and Punch Holders; and I do hereby declare the following to be a full, clear, and exact description of the invention, such as will enable others skilled in the art to which it appertains to make and use the same.

This invention relates to tool holders and has special reference to a chisel and punch holder designed to hold cold chisels and punches so that they can be struck by a hammer without fear of injuring the hand of the operator.

The principal object of the invention is to provide an improved and simplified device of this description which may be readily manufactured at a low cost.

Another object of the invention is to provide a tool holder or handle arranged to set at right angles to the tool, said handle being also arranged so that the tools may be quickly interchanged in the handle.

With the above and other objects in view the invention consists in general of certain novel details of construction and combination of parts hereinafter fully described, illustrated in the accompanying drawings, and specifically claimed.

In the accompanying drawings, like characters of reference indicate like parts in the several views, and Figure 1 is a top plan view of the device. Fig. 2 is a side elevation of the device. Fig. 3 is a longitudinal section on the line 3—3 of Fig. 1. Fig. 4 is a detail sectional view taken vertically 40 through the upper end of the device.

In carrying out the objects of the invention there is provided a hollow handle 10 having on each side thereof an elongated slot 11. At the forward end of this hollow handle is a head 12 which is provided with a centrally disposed opening 13. In this opening are certain guideways 14 and at the forward end of the opening is a rib 15 which is arranged to coöperate with a rib 50 16 on a guide head 17 formed on a plunger 18 movable in the hollow of the handle. Surrounding the plunger 18 is a spring 19

which normally urges said plunger forward, said spring bearing against a tractor bar 19' which projects through the slot 11. It 55 is to be noted that the rib 16 is arcuate as is also the rib 15. The punch or chisel shown at 20 is provided with a groove 21 intermediate its ends and when the punch or chisel is inserted in the tool holder this 60 groove is grasped between the ribs 15 and 16 and held centrally of the tool by reason of the guide head 17 fitting in the slot or guide portion 14 of said head. It will be obvious that by merely retracting the plunger 18 the tool 20 may be released from the head when engaged therewith and another tool put in place. It will be also obvious that the hand is held well away from the tool when in use so that a heavy blow may 70 be struck without danger of injuring the person holding the chisel.

There has thus been provided a simple and efficient device of the kind described and of the character specified.

It will be obvious that many minor changes may be made in the form and construction of this invention without departing from the material principles thereof. It is not therefore desired to confine the 80 invention to the exact form herein shown and described, but it is wished to include all such as come properly within the scope claimed.

Having thus described the invention, what 85 is claimed as new, is:—

A tool holder comprising a hollow handle, a head on the handle and communicating therewith, said head having aligned openings, a spring-pressed plunger-rod operating in the handle and having one end extending into the head, and a second head carried by the extended end of the plunger, each of said heads having a rib formed thereon and arranged in confronting relation for yieldably engaging a tool at diametrically opposite points when the tool is supported in the openings.

In testimony whereof, I affix my signature, in the presence of two witnesses.

OLE S. LE GRAND.
